UNITED STATES PATENT OFFICE.

WALTER J. KOHLER, OF SHEBOYGAN, WISCONSIN, ASSIGNEE TO KOHLER CO., OF KOHLER, WISCONSIN, A CORPORATION OF WISCONSIN.

BATH-TUB PATTERN.

1,159,395.

Specification of Letters Patent.

Patented Nov. 9, 1915.

Application filed August 3, 1914. Serial No. 354,616.

To all whom it may concern:

Be it known that I, WALTER J. KOHLER, a citizen of the United States, and resident of Sheboygan, in the county of Sheboygan and 5 State of Wisconsin, have invented new and useful Improvements in Bath-Tub Patterns, of which the following is a description, reference being had to the accompanying drawings, which are a part of this specification.

10 This invention has for its object to provide a bathtub suitable for being tiled into the walls and flooring of a room and relates to features of construction which adapt it to fit within a recess or a corner of a room or 15 against one wall of the room without forming open spaces between the tub and the wall or walls.

Another object of the invention is to produce patterns capable of positioning wings 20 or projections at desirable points for closing the spaces between the tub and the walls.

With the above and other objects in view the invention consists in the bathtub and the means for constructing the same as herein 25 shown and described and all equivalents.

Referring to the accompanying drawings in which like characters of reference indicate the same parts in the different views: Figure 1 is a side view of a bathtub constructed in accordance with this invention and installed in a right hand corner of a room: Fig. 2 is a plan view partly in section of the patterns arranged in accordance with this invention for constructing the bathtub 30 as shown in Fig. 1; Fig. 3 is a similar view showing an arrangement of the patterns for use in constructing a tub for fitting in a left hand corner: Fig. 4 is a similar view of the patterns arranged for constructing a tub for 35 fitting against one wall of a room: Fig. 5 is a similar view of the patterns arranged for constructing a bathtub for fitting in a recess: Fig. 6 is a detail sectional view of the 40 pattern for the roll rim attached to the tub pattern: and, Fig. 7 is a similar view of the pattern for the wall fitting rim attached to the tub pattern.

In these drawings 10 indicates the tub proper which is of enameled iron construction and has an integral rolled rim 11 around all of the exposed sides forming rounded corners at the portions between the adjacent exposed sides. At the other sides of the tub the rim is substantially flat and with angular corners so as to fit the corners of the 55

room, the edge of the flat rim portions being provided with an upwardly extending bead and a downwardly extending flange to be embedded in the wall behind the tiling thereof.

In order to close the space between the 60 sides and ends of the tub and the walls of the room there are wings 12 formed integral with the tub and extending from the rim to the floor and each provided with a bead at its edge to be tiled into the walls and floor. 65 The patterns for making a tub of this description, whether for use as a tub fitting against one wall of the room, a tub fitting in the right or left hand corner, or a tub fitting in a recess, may be made of one set 70 and adjusted to produce the characteristics desired. Thus the single tub pattern 13 may be combined with various rim patterns to form tubs of the various types mentioned, it being only necessary to change one or more 75 of the rim patterns to change from one form of tub to another. The rim of the tub pattern terminates along straight lines forming an eight sided parallelogram and a front rim pattern 14 corresponding in shape with the shape of the roll rim desired is secured 80 along one of the longer edges of the tub pattern while the back rim pattern 15 with an upwardly extending bead 16 and a downwardly extending flange 17 at its edge corresponding with the form desired for the 85 wall-fitting portion of the rim is secured to the opposite long edge of the tub pattern. These rim patterns may be secured to the tub pattern 13 in any desirable manner, as by 90 means of screws 18 passing through lugs 19 formed in the patterns as shown in Figs. 6 and 7. Two forms of end rim patterns may be employed, according to whether the end 95 rim is to be of the roll rim form or of the wall-fitting form. The end rim pattern 20 for the roll rim form is made in right and left, as shown in Fig. 4, with the rear end meeting with and conforming to the shape 100 of the rear rim pattern 15 and its front end rounded and meeting with and conforming in shape to the rounded roll rim of the front pattern 14. The end rim pattern 21 for wall-fitting portions of the rim is also made right and left, as shown in Fig. 5, with the 105 ends meeting and corresponding in shape with the back rim pattern 15 and front rim pattern 14. Thus the corner between two of the rounded portions of the rim is rounded when viewed in plan and the other corners 110

are right angular in shape. The end rim patterns 20 and 21 are secured to the tub pattern in the same manner as the other rim patterns and are interchangeable to convert 5 the pattern to any one of the four types of tub shown.

When the patterns are arranged to provide one of the roll rim patterns 20 at either end of the tub a wing pattern 22 is secured 10 beneath the back pattern 15 at that end and just beyond the curvature at the corner of the back pattern. This wing pattern may be secured to the tub pattern in any desired manner, preferably in the same manner that 15 the rim patterns are secured thereto. When however the wall-fitting end rim pattern 21 is arranged at either end of the tub pattern the wing pattern 22 is fitted beneath such end rim pattern 21, just beyond the curvature 20 of the corner of the tub pattern. In this manner the wings 12 are cast integral with the tub and its rim at such positions that they effectively close both ends of the 25 opening that is left between the tub and the wall of the room, whether the tub is of the form to fit against one, two or three walls of the room.

As the rim of the tub as well as the wings 12 and the base are designed to be tiled into 30 the wall and the floor of the room the tub is effectively sealed and no open space is formed difficult of access for cleaning.

What I claim as new and desire to secure by Letters Patent is:

35 1. A pattern for producing bath tubs adapted to be tiled in one or more walls of a room, comprising a tub pattern, a front rim pattern secured to the front edge thereof and being curved in cross section corresponding to the curvature of the roll rim desired, a back rim pattern secured to the rear edge of the tub pattern and being substantially flat to correspond in cross section to the flat wall-engaging portion of the tub rim, interchangeable end rim patterns adapted to be secured to the ends of the tub pattern and corresponding in cross section to the front rim pattern and to the back rim pattern respectively and having their ends meeting with and corresponding in shape to the front rim pattern and to the back rim pattern, and interchangeable end rim patterns adapted to be secured to the ends of the tub pattern and corresponding in cross section to the front rim pattern and to the back rim pattern respectively and having their ends meeting with and corresponding in shape to the front rim pattern and to the back rim pattern.

50 2. A pattern for producing bath tubs adapted to be tiled in one or more walls of a

room and to close the space between the tub 55 and the wall or walls of the room, comprising a tub pattern, a front rim pattern secured to the front edge thereof and being curved in cross section corresponding to the curvature of the roll rim desired, a back rim pattern secured to the rear edge of the tub pattern and being substantially flat to correspond in cross section to the flat wall-engaging portion of the tub rim, interchangeable end rim patterns adapted to be secured to the ends of the tub pattern and corresponding in cross section to the front rim pattern and to the back rim pattern respectively and having their ends meeting with and corresponding in shape to the front rim pattern 70 and to the back rim pattern, and wing patterns secured to the tub pattern at the corners thereof at which the rim patterns change from the flat rim shape to the roll rim shape.

3. A pattern for producing an enameled iron bath tub adapted to fit against one or more walls of a room with a roll rim at its exposed edges and a beaded and flanged flat rim at its wall-engaging edges and provided with wings for inclosing the space between the tub and the wall or walls of the room, comprising a tub pattern, a front rim pattern secured to the front edge thereof and having the shape in cross section of the roll rim desired, a back rim pattern secured to the rear edge of the tub pattern and having the shape in cross section of the wall-engaging rim as desired, interchangeable end patterns having the shape in cross section of the front rim pattern and the rear rim pattern respectively and having their ends meeting with and corresponding in shape to the front rim pattern and the rear rim pattern, the front ends of the end rim patterns of the roll rim type being rounded at their corners and the front ends of the end rim patterns of the wall-engaging rim type having right angle corners, and winged patterns secured to the tub pattern beyond 95 the corners thereof at which the rim changes from one type to the other.

In testimony whereof, I affix my signature, in presence of two witnesses.

WALTER J. KOHLER.
